UNITED STATES PATENT OFFICE

121,873

DESIGN FOR A GRINDING MACHINE

Milburn A. Hollengreen, Harold E. Balsiger, and
Donald F. Price, Waynesboro, Pa., assignors to
Landis Tool Company, Waynesboro, Pa.

Application June 6, 1940, Serial No. 92,865

Term of patent 14 years

To all whom it may concern:

Be it known that we, Milburn A. Hollengreen, Harold E. Balsiger and Donald F. Price, citizens of the United States of America, residing at Waynesboro, in the county of Franklin and State of Pennsylvania, have invented a new, original, and ornamental Design for a Grinding Machine, of which the following is a specification, reference being had to the accompanying drawing, forming part thereof.

Figure 1 is a front perspective view of a grinding machine showing our new design; and
Figure 2 is a rear perspective view thereof.

We claim:

The ornamental design for a grinding machine, substantially as shown.

MILBURN A. HOLLENGREEN.
HAROLD E. BALSIGER.
DONALD F. PRICE.
